UNITED STATES PATENT OFFICE.

OSWALD S. PULLIAM, OF PITTSBURGH, PENNSYLVANIA.

BOLSTER.

1,073,628.

Specification of Letters Patent. Patented Sept. 23, 1913.

Application filed March 14, 1910. Serial No. 549,105.

To all whom it may concern:

Be it known that I, OSWALD S. PULLIAM, a resident of Pittsburgh, in the county of Allegheny and State of Pennsylvania, have 5 invented certain new and useful Improvements in Bolsters, of which the following is a specification.

My invention relates to a new and improved bolster or transom for railway cars, 10 and more particularly to that class of bolsters consisting of an integral cast-metal structure.

In the accompanying drawings, which 15 illustrate applications of my invention, Figure 1 is a top plan of my bolster in the form of a truck-bolster; Fig. 2, a side elevational view of the form of Fig. 1; Figs. 3 and 4 vertical sectional views respectively taken on lines III—III and IV—IV of Fig. 20 2; Fig. 5, a perspective view of a modified form of bolster embodying my invention; Fig. 6, a vertical sectional view of the form of Fig. 5; and Fig. 7, a view similar to Fig. 6 showing a construction having curved 25 webs connecting the top and bottom member of a bolster.

Referring to the drawings, and first to the form of Fig. 1, 2 designates the top member of the bolster, 3 the bottom-member and 30 4 the column-bearing surfaces. As shown, the top-member is preferably formed with side-bearings 5 and a center-bearing 6. 7 designates a wall connecting the center-bearing and the bottom-member and is adapted 35 to receive the usual king-bolt. The top and bottom members are connected by two web-members 8 which latter extend throughout the length of the bolster proper and project beyond the ends thereof to enter into 40 the formation of the column-bearing surfaces 4. Web-members 8 are curved as shown at *a* at the center of the bolster and are spaced farther apart at the center than at other points in the length of the bolster 45 proper. Members 8 are disposed in vertical

planes lying wholly within the longitudinal edges of both the top and bottom members of the bolster proper, but in the form of Fig. 1, the ends thereof, beyond the bolster ends, are curved outwardly as shown at *b* 50 and form the column-bearing surfaces 4. The top-member of the bolster of the form of Fig. 1 is slightly wider than its bottom-member and the bolster has a central deepened portion. 55

In the form of bolster shown by Fig. 5, which is a modified form of bolster embodying my invention, the top-member 10 and the bottom-member 11 are connected by two web-members 12 of I-beam shape. In this 60 form, as in the form of Fig. 1, the members 12 lie in planes inside the longitudinal edges of the top and bottom members and extend throughout the length of the bolster.

The form of bolster illustrated by Fig. 7 65 is similar to the form of Fig. 5, with the exception that the web-members 13 are curved members.

What I claim is:

A bolster for cars consisting of an 70 integral metallic structure comprising a top member formed with a circular center-bearing and side-bearings, a bottom member, an annular king-bolt wall, and two spaced web-members connecting the top and bottom 75 members, said web-members each having a central curved portion extending under and reinforcing the center-bearing near its periphery, said curved portions being spaced away from the king-bolt wall, outer curved 80 portions extending under the side-bearings, and straight end portions, said latter portions forming column engaging members.

In testimony whereof I affix my signature in presence of two witnesses.

OSWALD S. PULLIAM.

Witnesses:

A. C. WAY,
W. G. DOOLITTLE.
